(57) **CLAIM**

The ornamental design for a tennis bag, as shown and described.

DESCRIPTION

FIG. 1 is a perspective view as seen from the top, front, and left side of a tennis bag of the present invention;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The broken lines in the figures showing conventional stitching, an identification window, and a mobile phone holder are for illustrative purposes only and form no part of the claimed design.

1 Claim, 4 Drawing Sheets
